Primary Examiner — Kevin K Rudzinski*Assistant Examiner* — Clare Ann Gannon(74) *Attorney, Agent, or Firm* — Gary E. Lambert; David J. Connaughton, Jr.; Lambert Shortell & Connaughton(57) **CLAIM**

The ornamental design for a separable tag for a collar, as shown and described.

DESCRIPTION

FIG. 1 is a rear perspective view of the separable tag for a collar, which embodies my design;

FIG. 2 is a front perspective view thereof;

FIG. 3 is a rear view thereof;

FIG. 4 is a front view thereof;

FIG. 5 is a top view thereof;

FIG. 6 is a bottom view thereof;

FIG. 7 is a right side view thereof;

FIG. 8 is a left side view thereof;

FIG. 9 is a front perspective view thereof, shown in an open configuration; and,

FIG. 10 is a rear perspective view thereof, shown in a separated configuration.
